Primary Examiner — Manpreet Matharu*Assistant Examiner* — Mojtaba Tehrani(74) *Attorney, Agent, or Firm* — Wolf, Greenfield & Sacks, P.C.(57) **CLAIM**

The ornamental design for a recreational flotation device, as shown and described.

DESCRIPTION

FIG. 1 is a perspective view of a recreational flotation device, showing my new design;

FIG. 2 is a right side elevation view thereof, with the left side elevation being the mirror image thereof;

FIG. 3 is a top plan view thereof;

FIG. 4 is a bottom plan view thereof;

FIG. 5 is a front elevation view thereof; and,

FIG. 6 is a rear elevation view thereof.

The broken lines in the drawing represent environmental subject matter and form no part of the claimed design.
